UNITED STATES PATENT OFFICE

132,592

DESIGN FOR A BADGE OR THE LIKE

Joseph H. Elliott, Charlottesville, Va.

Application February 25, 1942, Serial No. 105,984

Term of patent 3½ years

To all whom it may concern:

Be it known that I, Joseph H. Elliott, a citizen of the United States and resident of Charlottesville, in the county of Albemarle and State of Virginia, have invented a new, original, and ornamental Design for a Badge or the like, of which the following is a specification, reference being had to the accompanying drawing, forming part thereof.

Figure 1 is a plan view of a badge or the like, showing my new design, and

I claim:

The ornamental design for a badge or the like, as shown.

JOSEPH H. ELLIOTT.
